UNITED STATES PATENT OFFICE.

THOMAS A. COOPERRIDER, OF THORNVILLE, OHIO.

WELL-CAP.

No. 849,206.

Specification of Letters Patent.

Patented April 2, 1907.

Application filed January 20, 1906. Serial No. 297,018.

To all whom it may concern:

Be it known that I, THOMAS A. COOPERRIDER, a citizen of the United States, residing at Thornville, in the county of Perry and State of Ohio, have invented a new and useful Well-Cap, of which the following is a specification.

This invention relates to a device designed for use with board-wells constructed either 10 with or without a well-pit.

The object of the invention is to exclude dirt, and especially surface water or drainage, from the well-pipes.

The invention consists of the novel features 15 of construction hereinafter set forth, pointed out in the claims, and shown in the accompanying drawings, in which—

Figure 1 is a side elevation showing the application of my device to a pump, parts being 20 broken out and shown in section. Fig. 2 is a detail sectional view of the cap comprising a cover and casing bolted together. Fig. 3 is a plan view of the casing.

In the drawings, A represents a pump 25 mounted upon a suitable base A', which base rests upon a cover A'', extending over the well-pit.

My cap consists of a concaved cover or top B, which is centrally perforated and threaded, and a short pipe-section B' is threaded 30 into the said perforation and connects at its upper end with a pump-pipe B, and at its lower end with a well-pipe B''. Sleeves B'' are arranged, respectively, above and below 35 the top B and close the joints between the pipes B' and the pipes B'' and B''.

A barrel C incloses the well-pipe B'' and terminates a slight distance below the top B. A casing D is split lengthwise, as shown at D', 40 and is provided with two pairs of lugs, as shown at D'', and its upper portion is flared outwardly to form a bell-mouth D''. Within the casing and immediately below the bell-mouth D'' is an annular downwardly-curving shoulder E.

In use the barrel C extends upwardly within the casing, which is slipped over the end of the said barrel and forced down, so that the shoulder E engages the upper edge of the barrel, which edge is wedged between the said

shoulder and the inner face of the casing. The bell-mouth of the casing rests against the under face of the rim of the top B and is bolted to the same. The casing is locked in position upon the barrel C by bolts and nuts, 55 the bolts working through the lugs D''.

In case the well is not provided with a well-pit the cover (shown at A' in Fig. 1) serves as the top, and the casing D is bolted to said cover, as shown in dotted lines in 60 Fig. 1, or the cover A' is dispensed with and the top B substituted therefor, as the two are practically the same in construction. Packing material of any kind may be placed between the cap B and the casing D. 65

Having thus fully described my invention, what I claim as new, and desire to secure by Letters Patent, is—

1. The combination with a pump-pipe, of a concaved top, a barrel terminating short of 70 said top, a casing having a bell-mouth adapted to fit against the top, the said casing enclosing the upper portion of the barrel, and a shoulder within the casing, curving downwardly and adapted to bear upon and overlap the upper edge of the barrel. 75

2. The combination with a pump-barrel, of a casing split lengthwise from its lower end, a bell-mouth being formed at the upper end, an annular inwardly and downwardly curving shoulder formed in the casing between the bell-mouth and the inner end of the slot, and adapted to bear upon and overlap the upper edge of the barrel, and a top adapted to fit over the said casing. 80

3. A device of the kind described comprising a casing split longitudinally from its lower end, an interior downwardly-curving shoulder formed immediately above the inner end of the said slot, a bell-mouth formed on the casing above the said shoulder, a top having a central threaded perforation said top resting upon the bell-mouth, lugs carried by the casing adjacent the slot, and means for drawing the edges of said slot toward each other. 85

THOS. A. COOPERRIDER.
